(57) **CLAIM**

The ornamental design for the yarn feeders, as shown and described.

DESCRIPTION

1. Yarn feeder
2. Yarn feeder
- 1.1 : Perspective
- 1.2 : Front
- 1.3 : Right
- 1.4 : Back
- 1.5 : Left
- 1.6 : Top
- 1.7 : Bottom
- 2.1 : Perspective
- 2.2 : Front
- 2.3 : Right
- 2.4 : Back
- 2.5 : Left
- 2.6 : Top
- 2.7 : Bottom

Fig. 1.1 is a perspective view of the first design; Fig. 1.2 is a front view thereof; Fig. 1.3 is a right side view thereof; Fig. 1.4 is a rear side view thereof; Fig. 1.5 is a left side view thereof; Fig. 1.6 is a top view thereof; and Fig. 1.7 is a

(Continued)

bottom view thereof; Fig. 2.1 is a perspective view of the second design; Fig. 2.2 is a front view thereof; Fig. 2.3 is a right side view thereof; Fig. 2.4 is a rear side view thereof; Fig. 2.5 is a left side view thereof; Fig. 2.6 is a top view thereof; and Fig. 2.7 is a bottom view thereof.

The broken lines shown in the drawings represent portions of the yarn feeder that form no part of the claimed design.
